(57) **CLAIM**

The ornamental design for a hanging waste receptacle apparatus, as shown and described.

DESCRIPTION

FIG. 1 is a perspective view of a hanging waste receptacle apparatus showing my new design;

FIG. 2 is a front view of the hanging waste receptacle apparatus of FIG. 1;

FIG. 3 is a rear view of the hanging waste receptacle apparatus of FIG. 1;

FIG. 4 is a left side view of the hanging waste receptacle apparatus of FIG. 1;

FIG. 5 is a right side view of the hanging waste receptacle apparatus of FIG. 1;

FIG. 6 is a top plan view of the hanging waste receptacle apparatus of FIG. 1; and,

FIG. 7 is a bottom plan view of the hanging waste receptacle apparatus of FIG. 1.
